FLOOR CONSTRUCTION

Albert Henderson, Pittsburgh, Pa., assignor to
William P. Witherow, Pittsburgh, Pa.

Application April 12, 1939, Serial No. 267,397

3 Claims. (CL. 72—68)

This invention relates to a floor construction and, particularly, to a floor composed of precast members of concrete or the like which can be manufactured at relatively small expense and erected quickly in the field by unskilled labor.

The construction of floors in fireproof buildings according to present practice is a slow and costly procedure requiring highly skilled workmen. It is an object of this invention to provide a floor construction which can be erected quickly by unskilled labor, thereby reducing the overall cost of the building and the construction time required.

In a preferred form, the floor of my invention includes spaced supporting joists which are preferably precast from concrete or the like. The joists may be supported on the girders of a steel frame building or the principal beams of a reinforced concrete structure. The tread surface of the floor is formed of a plurality of precast slabs of concrete or the like extending between adjacent joists and disposed in side by side relation thereon. The slabs are preferably of channel shape in section and the upper edges of the joists have recesses formed therein to receive the flanges of the slabs which are disposed downwardly.

A thorough knowledge of the invention and its advantages may be gained from the following detailed description which refers to the accompanying drawing illustrating a preferred embodiment.

In the drawing:

Fig. 1 is a partial perspective view showing a section of a floor embodying the invention;

Fig. 2 is a section through the floor taken parallel to the joists;

Fig. 3 is a partial sectional view taken along the line III—III of Fig. 2;

Fig. 3—a is a similar view taken along the line IIIa—IIIa of Fig. 2;

Fig. 4 is a view in elevation showing the ends of the slabs and the side of a joist; and

Fig. 5 is a partial sectional view taken along the line V—V of Fig. 4.

Referring now in detail to the drawing, the floor of my invention comprises joists 10 suitably spaced apart and supported on the walls or frame of a building (not shown). Slabs 11 extend between adjacent joists and are disposed in side by side relation thereon providing a smooth, continuous tread surface. The joists 10 have longitudinal reinforcing bars 12 and 13 embedded therein and have their upper edges recessed as at 14 for a purpose which will appear shortly. The slabs 11 are of channel shape in section, each having flanges 15 and a web 16 which forms the tread

surface proper. As shown in the drawing, the flanges are disposed downwardly and are received in the recesses 14 in the upper edges of the joists 10. The slab flanges have reinforcing bars 17 embedded therein and a reinforcing mesh 18 extending over substantially the full area of the slabs. The ends of the transverse members of the mesh 18 are welded to the flange reinforcing bars 17.

As shown in the drawings, the joints between the joists and slabs are mortared as at 19. A longitudinal groove 20 extends along the upper edge of each slab thus providing a key for the mortar whereby transverse movement of the joists under the slabs is prevented, thus serving the function of the conventional cross bracing between floor joists.

Each slab 11 has a longitudinal groove therein. This may conveniently be provided by a rabbeted edge as illustrated at 21. The joists 10 are provided with tie wires 22 embedded therein and extending upwardly through the bottoms of the recesses 14 in the form of loops or eyes. The lower ends of the tie wires may conveniently be bent around one of the reinforcing bars in the joists, as shown in the drawing. Thus, when the slabs have been disposed on the joists, the loops 22 extend upwardly between the adjacent ends of slabs disposed in end to end relation, in alignment with the groove provided by the rabbeted edge 14. Tie rods or pins 23 may then be placed in the grooves and inserted through the loops 22, to anchor the slabs firmly to the joists.

After the slabs have been laid and anchored as described, the grooves formed by the rabbeted edges 21 and the spaces between the ends of the slabs are filled with grout and the floor is finished except for the application of a surface covering such as linoleum or the like.

It will be apparent that the invention is characterized by numerous advantages over conventional construction methods. The low cost and the quick erection which are made possible by the invention have already been mentioned. In addition, the flanges of the channel section slabs are effectively keyed to the joists by the recesses in the upper edges thereof so that the separation of the slabs or the opening up of longitudinal seams therebetween on shrinkage thereof is prevented. If any shrinkage occurs, the entire floor area must shrink together, both slabs and joists, since they constitute substantially a unitary or monolithic mass. A further advantage is the fact that the slabs have a T-beam action when loaded. The reinforcing mesh embedded in the

slabs, furthermore, provides ample resistance to shearing stress. The slabs and joists are locked transversely of the joists by the longitudinal grooves in the upper edges of the latter. Finally, 5 the slabs are firmly anchored to the joists in addition to being held down by their own weight.

The joists and slabs may be made in any convenient sizes and are preferably designed according to accepted standards, providing ample range 10 of choice for various applications.

Although I have illustrated and described but a preferred embodiment of the invention, changes therein may be made without departing from the spirit thereof or the scope of the appended 15 claims.

I claim:

1. A floor comprising spaced joists having a substantially plane upper edge with notches 20 therein at intervals therealong, and precast, channel-section slabs disposed side-by-side and extending between adjacent joists, each slab having flanges along the sides only and a web providing a tread surface, the flanges being disposed downwardly in said notches, said joists 25 having a longitudinal groove in the plane surface

thereof and also in the bottoms of said notches, providing a key for mortar between the slabs and joists.

2. A floor comprising spaced joists and precast 5 slabs disposed side by side and extending between adjacent joists, each slab having a rabbeted longitudinal edge providing a groove at the joint between the sides of abutting slabs, wire loops projecting above the upper edge of said joists through the joints between the ends of abutting 10 slabs, tie rods disposed in said grooves across said last-mentioned joints, said rods extending through said loops, and a filling of grout in said grooves and joints.

3. A floor comprising spaced joists and precast 15 slabs disposed side by side and extending between adjacent joists, each slab having a recessed edge providing a groove at the joint between adjacent surfaces of abutting slabs, wire loops projecting above the upper edge of said joists through the 20 joints between abutting slabs, tie rods disposed in said grooves across said last-mentioned joints, said rods extending through said loops, and a filling of grout in said grooves and joints.

ALBERT HENDERSON. 25
